UNITED STATES PATENT OFFICE.

HARRY C. GAMMETER, OF BRATENAHL, OHIO, ASSIGNOR TO THE AMERICAN MULTIGRAPH COMPANY, OF CLEVELAND, OHIO, A CORPORATION OF OHIO.

AUTOMATIC PAPER-FEED.

1,051,726.

Specification of Letters Patent. Patented Jan. 28, 1913.

Application filed January 13, 1910. Serial No. 537,798.

To all whom it may concern:

Be it known that I, HARRY C. GAMMETER, a citizen of the United States, residing at Bratenahl, in the county of Cuyahoga and 5 State of Ohio, have invented a certain new and useful Improvement in Automatic Paper-Feeds, of which the following is a full, clear, and exact description, reference being had to the accompanying drawings.

10 The object of this invention is to provide an efficient automatic paper feeding device. My paper feed may be used with various machines, as for example, a rotary duplicating machine.

15 The invention is in the nature of an improvement on the feeding device shown, described and claimed in my application, No. 529,495 filed Nov. 22nd, 1909, as a division of application 454,266. In those applications, the paper stands in a vertical block and is fed upwardly against a suitable separator which retards all but the foremost sheet. In the present invention, I feed from 20 the bottom of the vertical block of paper, and thereby obtain the advantage of having the paper automatically maintain itself by 25 gravity in feeding position, enabling the machine to operate without adjustment on various lengths of sheets.

30 Other features of the invention relate to the adjustments for insuring the proper feeding and separating of the paper irrespective of varying weight, thickness, stiffness, or moisture of the paper.

35 The present invention provides also improved means for pressing the block of paper toward the feeding roll.

40 The invention consists essentially of the combinations of parts which I employ in carrying out the above features as herein-after more fully explained and as definitely summarized in the claims.

45 In the drawings, Figure 1 is an end elevation of my paper feeding mechanism, and a rotary duplicating machine to which it is attached. Fig. 2 is a front elevation of the feeding mechanism. Fig. 3 is a detail, showing the driving rack and pinion, being in a plane parallel with Fig. 1 and looking 50 in the opposite direction. Fig. 4 is a vertical central section of the feeding mechanism. Fig. 5 is a rear elevation of the right hand portion of such mechanism. Fig. 6 is 55 a portion of axial section of the feeding roller. Fig. 7 is an end view of such roller.

Figs. 8 and 9 are views illustrating the adjustment of the supporting plate. Fig. 10 is a detail.

Fig. 1 shows the end plate 10 of a rotary duplicating machine of the type known as 60 the multigraph; it being understood that beyond this plate is a rotary printing member coöoperating with a parallel rotary platen, these two members, being mounted on the shafts 11 and 12 respectively and 65 geared together by the gears 13 and 14.

Any suitable means may be employed for rotating the couple, as, for example, the crank 15. As shown, the paper feeding mechanism is driven by the same rotating 70 means through the gear 16, meshing with the platen gear 14 and carrying a pinion 17 which meshes with a gear 18 on the shaft of which is a crank 19 driving a link 20 which operates the feed roller. It is to be 75 understood that other means may be employed for reciprocating the link, the means shown in Fig. 1 being simply illustrative.

The frame of the paper feeding mechanism comprises a pair of standards 21 and 80 22 which are shown as secured to the base plate 9 of the printing machine, and suitable cross rods 23 and 25, connecting the standards. The rods 23 and 25 carry a pair of plates 30, each plate having a wing 31 85 projecting forwardly at right angles to provide a back and side guides for a vertical block of paper standing on the base plate 32. The plates 30 are slidable in and out and are clamped to the rod 23 in adjusted position by suitable set screws 33. 90

Below the back plates 30 and toward the rear thereof is the shaft 35 on which is journaled the feeding roller 36. This roller as 95 shown consists of a fluted sleeve of soft rubber mounted on a metal shell 37 which has end plates 38 journaled on the shaft, as shown more particularly in Fig. 6. The plate 38 at the right hand end carries a pair of pawls 40 which are pressed by springs 41 against a ratchet wheel 42, rigid 100 on the shaft 35. On this shaft is a pinion 44 engaged by teeth 45 on the link 20 heretofore referred to, this link being slotted around the shaft and held against the end 105 of the pinion by a collar 46.

From the above described construction it will be evident that, as the printing member rotates, the reciprocation of the link in one direction is idle, and in the other direction 110

rotates the feeding roller 36. The parts are so proportioned that the link makes a complete reciprocation for each rotation of the printing drum, and the periodic movement thus given to the feeding roller 36 is at the proper time, with reference to the type form on the drum, so that the paper will be properly fed by the feed roller to the printing couple. The crank 19 is adjustable on its shaft (being locked by the set screw 48) and this enables the timing of the feed roller to be regulated as desired.

As has been stated, the paper to be fed stands in a vertical block on the base plate 32 and against the back plates 30 and between the side wings 31. The paper is given an even pressure against the plates 30 by the spring pressed rods 50 and 51 which bear against a suitable backing (of pasteboard, for example) on the outer side of the block of paper. These two rods are mounted in the ends of two pairs of arms 53 and 54, the arms of each pair crossing each other intermediately and being pivoted together at 55. The upper ends of the arms 54 are pivoted to the standards at 57, while the lower ends of the arms 53 are slotted, as shown at 58, and take around pins 59 on the standards. Suitable tension springs 60, engaging the two arms tend to draw them together, as shown in Fig. 1.

It will be noticed that the rod 50 stands a little farther away from the back plates 30 than the rod 51, and that the follower frame comprising the rods 50 and 51 and the levers 53 and 54 is drawn outwardly this difference increases, owing to the lower arm of the lever 53 being shorter than the other arms of the levers 53 and 54. This concentrates the feeding pressure of the follower frame at the lower rod, which is opposite the feeding roller, while the upper rod holds the paper vertical without binding it, leaving it free to be fed by the roller.

45 To insert the block of paper, the upper rod 50 is simply grasped by the operator's fingers and pulled outwardly, which moves outwardly the lower rod 51. In the extreme outward position of the rods an offset 62 of the slot 58, coming against the pin 59, holds the parts in this position against accidental displacement. Now the block of paper is put in place from the top at the rear of the rods 50 and 51 to rest on the plate 32. Then a sufficient pressure releases the slots 62 from the pins 59 and the spring 60 draws the rods 50 and 51 against the back of the block of paper whereby it is given a continuous pressure against the plates 30. This pressure may be regulated by changing the position of the springs 60, which are provided with hooked ends occupying any of the series of notches 63 on the arms 53 and 54.

65 With the paper standing on the plate 32

and pressed against the feed roll 36 by the spring follower frame, composed of the rods and arms mentioned, it will be seen that a left hand rotation of the feed roller will feed the foremost sheet downwardly, and this sheet will press into the rearwardly extending space between the underside of the feed roller and the plate 32, and thence passes horizontally to the printing couple. Now to enable the feed roller, on the one hand, to grasp stiff and smooth sheets with sufficient force to feed them, and, on the other hand, to act lightly enough on flexible and rough papers, so that only one sheet is fed, I provide certain adjustments, which, while being very simple in operation and few in number, have been found very effective in practice. These adjustments and the manner by which they are effected, will now be described.

The plate 32 inclines downwardly toward the feed roller, as shown in Figs. 1 and 4. Near its inner end, this plate is provided with a pair of ears 70 by which it is pivoted to a rocking yoke 71, which is pivoted on bosses on the standards surrounding the shaft 35. At its mid portion the yoke 71 carries a set screw 72, which operates through a slot in the arcual keeper bar 74. Near its inner end the plate 32 projects beneath the feed roller and at its extreme end is provided with an upwardly extending curve 75; near its rear end the plate 32 rests on a rocking frame shown as composed of a rod 76 and supporting rock arms 77 on a rock shaft 78 journaled in the standards 21 and 22. This rock shaft is provided with a knurled head 79 by which it may be turned and it is locked in desired position by a set screw 80. A suitable supporting plate 82 is provided for directing the separated sheets of paper, this plate extending from a position below the inner end of the plate 32 toward the printing mechanism, or other mechanism, which is to receive the fed sheet.

When the feed roller is rotated in the left hand direction, the sheet of paper which it engages, and very likely two or three other sheets, are fed downwardly and forwardly, and these sheets engage the curve 75. This curve introduces sufficient resistance to the movement of the paper that all the sheets except the foremost one are stopped thereby, but the resisting force is not as great as the feeding force of the soft rubber roller 120 on the foremost sheet, so that this sheet instead of being stopped by the curve buckles over at its forward edge and passes over the top of the curve and onto the plate 82. Now it will be seen that by swinging the yoke 71 125 the curve is carried forwardly (toward the printing mechanism) or rearwardly, and the farther forward it is the more space is provided for the sheet to curve around the roller. The swinging of the yoke away 130

from the printing mechanism reduces the space for curving the sheet being fed and moreover may swing the supporting plate 32 nearer to a horizontal position. The 5 steeper the incline of the supporting plate, the more active is the feeding action caused by gravity. The result is, that with stiff paper, requiring considerable space to allow its edge to be bent, the yoke is swung to 10 toward the printing mechanism. This may also give a greater incline to the supporting plate 32, whereby the feeding action is increased. On the other hand with light paper the yoke is swung away from the printing mechanism reducing the space, thus 15 giving less chance for the feeding of more than one sheet. Frequently the only adjustment necessary for various grades of paper is the shifting of the yoke 71. The 20 normal pitch however of the plate 32 may be changed by elevating or lowering the rod 76, and this, together with the adjustment of the spring follower frame, provides 25 effective means for varying the feeding action and compensating for peculiarities in the paper.

The adjustments of the supporting and separating plate are illustrated in Figs. 8 and 9, the former of which shows the plate 30 in a position, for example, with light thin paper and the latter for use with heavy or stiff paper. The block of paper in these figures is indicated by X and the foremost sheet 35 by x, and the difference in the curve of this foremost sheet and the space allowed for it, is illustrated in the two figures. The incline of the supporting plate is considerably steeper in Fig. 9, both by reason of its pivotal support being lower, and its outer support, by the rod 76, being higher.

One curve 75 will operate satisfactorily for a considerable range of variation in the paper, but for great variations, it may be desirable to have interchangeable plates with 45 curves of different radii. This is illustrated in Figs. 8 and 9, the radius of the curve 75 in Fig. 8 being much shorter than the corresponding radius 75^a in Fig. 9.

To allow the convenient interchange of 50 plates 32, I provide them with suitable latches by which they are removably carried by the yoke 71. These latches are illustrated in Fig. 10 and comprise the ears 70, referred to, and pivoted arms 84 mounted 55 thereon, the ear having an upwardly extending notch and the arm a corresponding downwardly extending notch so that the two may coöperate to embrace the pin 85 projecting from the yoke. The friction between 60 the arm 84 and the ear 70 normally holds these parts in place. The axis of the pins 85 is in line with the edge of the curve 75, so that the adjustment of the plate about the roller does not change the distance between 65 the roller and the edge of the plate.

It will be seen from the description above given that the necessary adjustments are few. The crank 19 is set by trial according to the position of the type-form on the drum and the amount of letter-head printing, or a blank space desired, on the sheet. The side plates 31 are adjusted accordingly to the width of the sheets. The springs 60, the incline of the plate 32, and the position of its curved edge are mutually adjusted according to the peculiarities of the paper, it being remembered that the harder it is for the feed roller to advance the sheets (whether due to their smoothness, their stiffness or otherwise) the less should the paper be held back by the retarding curve and the angle through which the paper must bend, while the spring follower-frame should press the block against the roll with increased pressure. On the other hand, with light and easily fed sheets, the contrary adjustment is the rule.

Having thus described my invention, what I claim is:

1. In a paper feeding mechanism, the combination of a feeding roller, an upright plate to which it is substantially tangent, a plate for supporting in a plane the bottom edge of an upright block of paper, and means for pressing the paper against the upright plate and roller, the supporting plate continuing beneath the roller and being provided behind the plane of the upright plate with a sharp curve for retarding the forward edge of the fed sheets.

2. In a paper feeding mechanism the combination of a rotatable roller having a soft peripheral surface, an upright plate to which the roller is tangent, a plate for supporting at the bottom an upright block of paper with the roller in contact with such block adjacent to the bottom thereof, said supporting plate being a plane where it supports the block of paper and merging into an upwardly extending curve beneath the roller and behind the plane of the upright plate, and a spring pressure device on the opposite side of the block of paper pressing it against the upright plate and roller.

3. In a paper feeding mechanism, the combination, of a member having an inclined upper plane surface and arranged to engage the bottom edge of an upright block of paper and to support such paper, an upright plate against which the paper stands, and a feed roller on that side of the paper toward which such surface inclines downwardly, the front of said feed roller being substantially tangent to the face of the plate, the said member continuing beneath the roller and there merging with an upwardly extending curve which is behind the plane of the plate and having its angle adjustable independently of the roller.

4. In a paper feeding mechanism, the

combination of a member having an inclined upper surface and arranged to engage the bottom edge of a block of paper and to support such paper, a feed roller on that side 5 of the paper toward which such surface inclines downwardly, the said surface continuing toward the roller beyond the plane of the paper engaging it, and merging into a curved retarding edge located behind said 10 plane, means for adjusting the member independently of the roller, and a spring pressed follower on the opposite side of the paper from such roller.

5. In a paper-feeding mechanism, the 15 combination with a rotatable feed roller, of a plate extending at an angle across the end of a block of paper and extending transversely of the feed roller, there being a curve adjacent to the extreme end of said 20 plate and adjacent to the feed roller, and means for adjusting the said angle and means for independently adjusting the position of the curve about the feed roller.

6. In a paper-feeding mechanism, the 25 combination with a rotatable feed roller, of a plate adapted to extend across the lower end of a block of paper and support the same, said plate extending transversely of the feed roller and merging into an abrupt 30 upwardly extending curve at the extreme end of said plate and beneath the feed roller, and means for adjusting the plate both as to its angle and bodily.

7. In a paper-feeding mechanism, the 35 combination with a rotatable feed roller, a member adapted to move about the axis of the rollers, and a stop-plate for the paper having a retarding device and connected with said member whereby the position of 40 such device may be adjusted.

8. In a paper-feeding mechanism, the combination with a rotatable feed roller, a member adapted to move about the axis of the roller, and a stop-plate for the paper 45 having a retarding curve and connected with said member, whereby the position of such curve may be adjusted with reference to the roller.

9. In a paper feeding mechanism, the 50 combination of a rotatable feed roller, a yoke mounted to swing about the feed roller, and a movable paper support and retarding device mounted to swing with said yoke.

10. In a paper-feeding mechanism, the 55 combination with means for holding paper, of a rotatable feeding roller, a yoke mounted to swing about the axis of the roller, a clamp for holding the yoke in various adjusted positions, and a stop-plate having a 60 retarding edge carried by said yoke.

11. The combination, with a paper-feeding roller, of a support for the paper continuing beneath the roller and there having a retarding edge, and means for adjusting 65 the position of such edge toward or from

the block of paper while substantially preserving its presentation to the roller.

12. In a paper-feeding mechanism, the combination of a rotatable feeding roller, a supporting plate for the paper standing in front of the roller and extending beneath it, and a yoke movably mounted about the axis of the roller and carrying the forward end of said plate whereby the position of the plate may be adjusted while substantially preserving its presentation to the 75 roller.

13. The combination, with a feeding roller, of a yoke journaled coaxially, a slotted arcual keeper for the yoke extending transversely of it, a set screw passing through the slot clamping the keeper and yoke, and a supporting plate for the paper, the forward end of which is carried by said 80 yoke beneath the roller.

14. In a paper-feeding mechanism, the combination with a feeding roller, an inclined supporting plate for a block of paper, said plate extending beneath the roller, and means for swinging the forward edge of the 90 plate about the axis of the roller and thereby simultaneously changing both the distance of the edge from the block of paper and the incline of the support for the paper.

15. In a paper-feeding mechanism, the combination with a feeding roller, an inclined support for a block of paper, said support extending beneath the roller and carrying beneath the roller a retarding edge and means for swinging the forward edge 100 of the support about the roller and thereby simultaneously changing both the distance of the edge from the block of paper and the incline of the support for the paper, and means for adjusting the incline independently of the position of the forward edge.

16. In a paper-feeding mechanism, the combination of a roller, a plate pivoted beneath the same and adapted to support a 110 block of paper acted on by the roller, and a pivotally mounted rocking frame engaging the underside of the plate independently of the pivot of the plate for supporting said plate at various angles.

17. In a paper-feeding mechanism, the combination with a feed roller, of a supporting plate for a block of paper, means for carrying said plate near one end beneath the roller, a pair of rock-arms, a rod carried thereby for supporting the plate near its outer end, said rod freely engaging the plate and slideable along its under side, and means for clamping said outer-end support in various positions.

18. In a paper-feeding mechanism, the combination, with a feed roller, of a back stop against which a block of paper may bear, two pairs of crossing arms and two rods connecting the arms of the two pairs, 130

respectively, said rods being adapted to bear against the other side of such block of paper, and a spring tending to move said rods toward the back-stop.

- 5 19. In a paper - feeding mechanism, the combination with a back-stop against which a block of paper may bear, of two pairs of arms, the arms of each pair crossing each other and being pivoted together at the crossing; a tension spring for each pair of arms acting on both arms of the pair, and means connecting the two pairs and adapted to bear against the other side of such block of paper.
- 10 20. In a paper - feeding mechanism, the combination of a feeding roller, of a follower frame having two pairs of crossing mutually pivoted arms, a spring on each pair of arms engaging both arms of the pair and tending to draw them together, the arms being provided with a series of notches at varying distances from the pivot in which notches the spring is adapted to be anchored.
- 15 21. In a paper-feeding mechanism, a follower frame having two pairs of mutually crossing and pivoted arms, and means connecting the pairs, one arm of each pair having a pivotal support and a sliding guide for the other arm of each pair, the arm which has the sliding guide being provided with means for holding the arm in extreme position.
- 25 22. In a paper - feeding mechanism, the combination, with a feed roller, of a back-stop, a spring actuated follower frame adapted to press the paper against the stop at two separated points, one of which is

more distant from the feed roller than the other, and means whereby the pressure is lighter at the point more distant from the feed roller.

40 23. In a paper - feeding mechanism, the combination of a feed roller, a follower frame having a pair of cross rods adapted to press the paper toward the roller, one of said cross rods being more distant than the other from the plane of the paper, and means for moving said rods away from the roller concurrently, the more distant rod moving more rapidly.

45 24. In a paper - feeding mechanism, the combination of a rotatable feed roller, an inclined supporting plate for the bottom of an upright block of paper in front of the feed roller, the supporting plate having a 50 retarding edge beneath the feed roller, a follower on the opposite side of the block of paper from the feed roller, and means for adjusting the pressure of the follower and the incline of the supporting plate and the position of the retarding edge.

55 25. In a paper feeding mechanism, the combination, with a feed roller, of a supporting plate having a curved retarding edge, and a latch for removably and pivotally holding said plate near its curved edge.

60 In testimony whereof, I hereunto affix my signature in the presence of two witnesses.
